FRAME OF MEDICAL X-RAY TELEVISION APPARATUS

Seijsiro Umezono, Yokohama, Japan, assignor to Tokyo
Shibaura Electric Co., Ltd., Kawasaki-shi, Japan

Filed Nov. 27, 1972, Ser. No. 309,776

Term of patent 14 years

Int. Cl. D24—01

U.S. Cl. D83—1 H

FIG. 1

FIG. 4

FIG. 2

FIG. 3

FIG. 5

FIG. 6

FIG. 7

FIG. 1 is a top plan view of a frame of medical X-ray television apparatus showing my new design;

FIG. 2 is a front elevational view thereof;

FIG. 3 is a bottom plan view thereof;

FIG. 4 is a left side elevational view thereof;

FIG. 5 is a right side elevational view thereof;

FIG. 6 is a rear elevational view thereof; and

FIG. 7 is a perspective view thereof.

I claim:

The ornamental design for a frame of medical X-ray television apparatus, as shown.
